UNITED STATES PATENT OFFICE.

JOHN J. VÖGLER, OF DOUGLASTON, NEW YORK, ASSIGNOR TO ALFRED H. SMITH CO.,
OF NEW YORK, N. Y., A CORPORATION OF NEW YORK.

POWDER BOX.

Application filed May 21, 1925. Serial No. 31,732.

This invention relates to certain improvements in containers or cases for loose powder.

Loose powder for toilet purposes is now largely sold in bulk, that is, is put up in relatively large quantities, as, for instance, a pound or more. This bulk powder is used particularly for dusting after bathing, although, of course, it may be used for facial or other purposes. As this powder is now put out, it is packaged in a container with which is supplied a large puff for applying the powder, the container being opened and the powder extracted therefrom in the usual manner. As this powder is now put up, to be carried around it is necessary to carry the whole package or to transfer part of the powder to another receptacle, which may or may not be powder tight, so that there is danger of leakage of the powder.

It is the especial object of the present invention to provide an improved container for bulk powder which shall be provided with a closure which in itself is a powder carrier, this closure being constructed to carry a puff, and so that it is practically proof against accidental loss of powder; this closure forming a cover for the case or box in which the bulk powder is packaged, so that a user can put into this closure a sufficient amount of powder for one or two applications, the closure being of such size as to be readily carried around.

It is a further object of the invention to produce an improved box or case for bulk powder in which the case is provided with a supplemental cover by which the box can be covered or closed when the closure is removed, the invention having for a further object the provision of a dispensing means in this supplemental cover.

With these and other objects not specifically referred to in view, the invention consists in certain novel parts, arrangements and combinations which will be described in connection with the accompanying drawings and the novel features pointed out in the claims hereunto appended.

In these drawings,--

Figure 1 is a perspective view of the improved package;

Figure 2 is a central vertical section taken on the line 2-2 of Fig. 1, showing the closure and supplemental cover in position;

Figure 3 is a detail sectional elevation

showing the package with the closure removed and the supplemental cover in its operative position;

Figure 4 is a sectional plan view of the construction shown taken on the line 4-4 of Fig. 2;

Figure 5 is a sectional view on a smaller scale than the other figures showing the closure and its associated cover;

Figure 6 is a sectional view of the cover for the closure;

Figure 7 is a sectional view of the closure with the cover removed;

Figure 8 is a sectional view of the supplemental cover, and

Figures 9 and 10 are detail sectional views of a powder drum or carrier which may be used in the box.

Referring now to these drawings, the invention is illustrated as embodied in a can of light metal and circular in shape. It will be understood, however, that such a can has been selected merely as illustrative, and the invention is not to be restricted to such shape or such material. As shown, however, there is provided a can of light metal marked generally 1, this can being capacitated to carry the desired amount of bulk powder indicated by P, as, for instance, a pound. This box body is provided with side walls 2 which may be, if desired, turned over at the top, as indicated at 3, to form a strengthening flange. The body 1 is provided with a bottom 4 having a downwardly extending flange 5 which is bent upwardly, as indicated at 6, to form a recess for the reception of the walls 2 of the box, these walls being held in the groove and pinched in by squeezing up the metal so as to firmly hold the parts together, this construction forming a strong rigid body.

This body 1 is capacitated, as before stated, to carry the desired amount of powder; and this powder, if desired, may of course be put loosely in the body. In the preferred construction, however, the powder will be carried in a container or drum which may be, as illustrated, of two parts, an outer walled receptacle 7 having a bottom 8 and an inner walled receptacle 9 open at the bottom but provided with a top 10 of some easily frangible material, as paper. In assembling the parts the powder is placed in the receptacle 7 and the receptacle 9 forced down so as to occupy the position shown in

Fig. 2, the paper 10 being clamped between the walls of the parts 7 and 9.

Closing the box body 1 is a closure which forms an important feature of my invention. This closure is capacitated to carry a desired amount of powder and a powder puff, and the closure is provided with a lid. This closure is associated with the box body so as to have a tight friction fit and prevent the accidental escape of powder, and the lid or cover for the closure is so arranged and so cooperates with the puff as to effectually seal the powder in the closure and prevent accidental escape of the powder therefrom.

While the specific construction of this closure may vary to some extent, it will conform to the shape of the box, both being circular in the present instance. This closure is provided with a central dished portion 11 which is extended upwardly, as indicated at 12, and then outwardly, as indicated at 13, to form a horizontal flange. This flange is extended upwardly to form a vertical flange 14 which has a tight friction fit with the inner surface of the walls 2 of the box body. Preferably, the metal of the closure is also bent upon itself, as indicated at 15, to form a flange which will rest on the top 3 of the walls 2 of the body, this flange 15 extending inwardly and then upwardly to form a vertical flange 16, this vertical flange being bent upon itself, as indicated at 17, to form a strengthening rib.

Cooperating with this closure is a cover or lid 18 which is provided with a horizontal rib 19 which rests on the rib 17 of the closure and a downwardly depending flange 20, this flange being slightly longer than the flange 16 so that it projects below this latter flange. The flange 13 of the bottom of the closure is provided with an annular groove 21, this groove being located preferably below the flange 20 of the cover or lid when the latter is in position. Carried in the closure is the desired amount of powder, indicated at P', and above this powder is located a puff or other applicator, preferably of flexible material, 22. It will be observed that when the parts are in closed position, as shown in Fig. 2, the flange 20 compresses the applicator and forces it into the groove 21, so that the applicator acts as a seal and prevents the accidental escape of powder from the box.

Furthermore, for shipping purposes, it will be observed that the dished bottom 11 of the closure is arranged so as to bear with slight pressure on the surface of the paper 10 of the powder containing drum, so that this latter is held firmly in position in the body.

It will be seen with this construction that the closure may be filled with the desired amount of powder and removed from the

body and, being powder tight, can be conveniently carried in a handbag or any desired way for use as desired. In constructions embodying the invention in its best form means will be provided for covering the box body when the closure is removed, and in the best constructions these means will include a distributing device by which powder may be removed from the box body for the purpose of filling the closure. While various means may be provided for accomplishing this, in the particular construction illustrated the box body is provided with a supplemental lid which is conveniently arranged as a false bottom. In the particular construction shown, this lid is in the form of a cap or plate 23, the peripheral edges of which are formed with a groove 24. This groove is adapted to receive the flanged bottom 5, 6 of the box body and, owing to the depth of the flange 5, this cover or lid will extend into the space beneath the bottom of the box body. This plate is dimensioned so that it will have a snug fit over the top 3 of the walls 2 of the box, as shown in Fig. 3, this plate when used as a cover being in a position reverse to that shown in Fig. 2. This lid or cover is provided with a distributing orifice, which is conveniently formed by slitting and bending up slightly the material of the plate, as indicated at 25 in Fig. 3.

With the construction shown and described it will be seen that a very convenient and powder tight package has been provided, one that is convenient to use, both in the home and in which a sufficient amount of powder may be carried separately from the main body as desired. While the invention has been shown and described in a practical form, it will, of course, be understood that certain changes and variations may be made in the structure disclosed without departing from the invention as defined in the claims hereunto annexed.

What I claim is:

1. In a powder receptacle, a box body for containing a relatively large amount of loose powder, a removable closure therefor, said closure having a bottom closed to the powder in the body and capacitated to hold a smaller amount of loose powder, a puff in the closure, and a cover and closure having cooperating parts engaging with and for the closure, said cover acting to lock the puff over the powder and prevent escape of powder when the cover is in position.

2. In a powder receptacle, a box body for containing a relatively large amount of loose powder, a removable closure therefor, said closure having a bottom closed to the powder in the body and capacitated to hold a smaller amount of loose powder, a puff in the closure, a cover for the closure, said cover and closure having cooperating parts

engaging with and acting to lock the puff over the powder and prevent escape of powder from the closure when the cover is in position, and a supplemental cover detachably secured to the box body for closing the body when the closure is removed.

3. In a powder receptacle, a box body for containing a relatively large amount of powder, a removable closure therefor, said closure being capacitated to hold a smaller amount of powder, a puff in the closure, a cover for the closure, said cover acting to lock the puff over the powder and prevent escape of powder from the closure when the cover is in position, a supplemental cover detachably secured to the box body for closing the body when the closure is removed, and a distributing orifice in the supplemental cover through which powder may be removed from the body when the closure is removed and the cover in place.

4. In a powder receptacle, a box body having a bottom flange and a rim, a closure therefor having a body in frictional engagement with the inner wall of the rim, a cover for the closure, and a supplemental cover having a flange in frictional engagement with the inside of the bottom flange of the body in one position and a flange having frictional engagement with the outer wall of the rim when the supplemental cover is reversed.

5. A powder holder comprising a receptacle having a powder holding compartment, a loose puff in the compartment above and contacting with the powder, and a lid for the compartment having a locking flange engaging with and acting to lock the puff in position in the closure and prevent the escape of powder around the edges of the puff when the cover is in position.

6. In a powder holder, a receptacle having a powder holding compartment, a locking groove surrounding the powder holding compartment and located above the bottom thereof, a loose puff extending over and in contact with the powder in the compartment and the locking groove, and a lid having a locking flange acting to compress the puff into the locking groove when the lid is in position.

7. In a powder holder, a powder holding compartment, a flange extending laterally of said compartment and above the bottom thereof, a groove in the flange, an inwardly projecting flange above the lateral flange, a puff in the compartment extending over the powder and the groove, and a lid having a flange projecting downwardly inside of the inwardly extending flange and acting to lock the puff in the groove when the lid is in position.

8. In a powder receptacle, a box body for containing a relatively large amount of powder, a removable closure therefor, said closure having a close friction fit with the interior walls of the body, a puff in the closure, a vertically extending flange at the upper edge of the closure, and a cover for the closure having a depending flange in close frictional contact with the vertical flange of the closure and extending below the same and acting to lock the puff over powder in the closure and prevent escape of powder around the upper face of the puff.

9. In a powder receptacle, a box body for containing powder, a bottom therefor inset from the lower edge of the box walls, a detachable cover having a grooved flange frictionally engaging the inner walls of the bottom, the groove of said flange being proportioned so as to frictionally engage the top wall of the box body when the cover is in reverse position, a closure for the box body capacitated to carry a small amount of powder, a puff in the closure, and a cover for the closure and engaging the puff.

10. A powder receptacle comprising a box body, and a closure therefor, said closure being capacitated to hold powder and a puff, a horizontally extending flange near the bottom of the closure, a lower vertical flange having a close friction fit with the walls of the body, an upper vertical flange, and a lid having a depending flange having a close friction fit with the upper flange, and depending below said flange interiorly of the closure.

In testimony whereof, I have hereunto set my hand.

JOHN J. VOGLER.

CERTIFICATE OF CORRECTION.

Patent No. 1,616,834.

Granted February 8, 1927, to

JOHN J. VOGLER.

It is hereby certified that error appears in the printed specification of the above numbered patent requiring correction as follows: Page 2, lines 119 and 120, claim 1, strike out the words "and closure having cooperating parts engaging with and" and insert the same to follow after the word "cover" in line 120, same claim; and that the said Letters Patent should be read with these corrections therein that the same may conform to the record of the case in the Patent Office.

Signed and sealed this 29th day of March, A. D. 1927.

M. J. Moore,
Acting Commissioner of Patents.

Seal.
